UNITED STATES PATENT OFFICE

2,170,864

MACHINE FOR MANUFACTURING STRAP SANDALS

Jacob S. Kamborian, Newton, Mass., assignor to
United Shoe Machinery Corporation, Paterson,
N. J., a corporation of New Jersey

Application April 4, 1938, Serial No. 199,878

10 Claims.

(Cl. 12—1)

This invention relates to machines for manufacturing strap sandals and other shoes of the type in which the shoe is adapted to be retained in place upon the foot by straps or the like which extend upwardly from edge portions of the sole.

It has heretofore been common practice in the manufacture of strap sandals to assemble straps with an insole secured to a last, to stretch the straps over the last, and to secure them in overlaid position by means of fastenings such as tacks or staples driven through the straps and into the insole.

It is an object of the present invention to provide an improved machine for use in making strap sandals and which is especially adapted to facilitate the assembling of the insole and straps.

To this end, and as illustrated, the invention provides a machine comprising strap severing mechanism, mechanism for feeding a predetermined length of strip material past the severing mechanism by means of which a piece is severed from the leading end of the strip material to provide an individual sandal strap, together with mechanism operable to spray adhesive upon an insole presented to the machine, for wiping the end of a strap over the portion of the insole to which adhesive has been applied and for driving a fastening through the end of the strap. This construction is advantageous in that it facilitates the assembly of the straps and the insole and requires little handling of the shoe and strip material during the strap attaching operation.

These and other features of the invention are disclosed in the following specification and in the accompanying drawings, and are pointed out in the claims.

In the drawings:

Fig. 1 is a view in side elevation of a machine embodying one form of my invention;

Fig. 2 is a plan view partly in cross section of the machine shown in Fig. 1 showing a shoe in operative position relative to the strap securing instrumentalities;

Fig. 3 is an end view of a portion of the strap feeding mechanism;

Fig. 4 is a view in front elevation of a portion of the machine showing the strap securing instrumentalities;

Fig. 5 is a plan view illustrating the operation of spraying the cement upon an insole;

Fig. 6 is a plan view illustrating the portion of the wiper at the end of the wiping operation; and

Fig. 7 is a view representing a portion of a shoe on a last showing the straps secured in position on the shoe.

Fig. 1 of the drawings illustrates the invention as applied to a machine for driving tacks and having a frame 10 carrying a tack nozzle 12 toward which strip material or strapping S is advanced by a feed roll 14 past cutting off mechanism comprising knives 16 and 18, a spray device 20 located adjacent to the nozzle for spraying cement upon a portion of an insole 22 on a last 24, and a wiper 26 for wiping a portion of the end of the strapping over the insole along the 10 surface to which the cement has been applied. The machine is provided with the usual tack driver 27, raceway 28, and tack separator 30, the various mechanisms being driven from a main shaft 32. The tack inserting mechanism may be 15 of any well-known type, that herein illustrated corresponding to that of the machine illustrated in United States Letters Patent No. 1,106,393, granted August 11, 1914, upon an application filed in the name of F. L. MacKenzie.

The strapping S, which may be flat tubular braid or other strip material, is wound upon a reel 34 carried by a bracket 36 on the frame and is advanced toward the nozzle 12 through a flat tube 38, Figs. 2 and 4, by means of the feed roll 25 14. The feed roll 14 is mounted upon a shaft 40, Fig. 2, on a bracket 42 carried by the frame and has on its outer end a disk 44 which is covered with a friction material such as leather 46. The disk 44 is forced outwardly by means of a 30 spring 48 and is caused to engage a similar disk 50 which is splined to a vertical spindle 52, Figs. 1, 2 and 3, positioned in bearings 54 on the machine frame and arranged to be rotated by gears 56, 58, 60 and 62, the last of which is mounted upon 35 the main shaft 32. It is to be noted that the friction disk 50 is movable in a heightwise direction along the spindle 52 so that its position radially of the disk 44 can be varied with the result that the rotation of the disk 44 during one revolution 40 of the disk 50 will also be varied so that the strip S will be advanced different distances beyond the knives 16 and 18 depending upon the location of the disk 50 outwardly of the disk 44. When the edge of the disk 50 is located at the center of the 45 disk 44 the rotation of the former will not result in any feed movement of the roll 14. The length of feed of strapping for any one cycle of operations of the machine can readily be adjusted by turning knob 64 on a shaft 66 carried by a sleeve 68 and having on its rear end teeth 70 which mesh with a vertically slidable rack 72. The rack carries at its upper end a fork 74 arranged to engage the walls of a slot 76 on the mounting of the disk 50 with the result that the disk 50 can 55

readily be adjusted radially of the disk 44 to vary it to the extent of feed movement of the roll 14. A collar 78 on the shaft 66 bears a scale, preferably in inches, by which the amount of feed of 5 the feed roll is indicated.

In order to guide the strip material from the reel 34 to the tube 38 I have provided a plate 80 rotatably mounted upon an arm 82 of a bell-crank lever pivoted to the frame at 84, the other arm 10 86 of which is engaged by a spring 88 normally operative to force the arm in a clockwise direction (Fig. 3) to press the edge of the plate 80 down upon an apron 90 at the outer end of the tube 38. The edge of the plate is notched as 15 indicated at 92 to provide recesses of different widths adapted to receive different widths of material as required. The proper notch is located relatively to the apron by forcing the arm 82 in an upward direction against the spring 20 88 and rotating the plate 80. This mechanism is such that the strip material from the reel will be guided to the tube 38 during its feed movement regardless of the width of the material.

The strip material advanced by the feed roll 25 14 passes over an idler roll 94 mounted upon a rotatable stud 96 so that the axis of the roll is eccentric to the axis of the stud. The stud 96 carries a depending handle 98 which is urged in a clockwise direction by a spring 100. The 30 construction is such that the spring 100 normally causes the stud to rotate in a direction such that the idler roll 94 is yieldingly forced in a direction to press the strip material against the feed roll 14. When a new reel of strip material 35 is introduced into the machine the handle 98 is moved in a counterclockwise direction to move the idler 94 away from the roll 14 so that the end of the strip material can be inserted between the rolls.

40 The strip material or strapping S is guided in the tube 38 at a point near the severing mechanism which is located just beyond the forward end of the tube by means of two guide pins 102 carried by a bridging member 104 positioned above 45 the top of the tube, the pins being arranged to enter openings in the tube and to extend therein. The pins 102 are so spaced apart that they will serve to limit lateral movement of a strip passing through the tube so that strips, particularly 50 narrow strips, will be guided in a direction substantially normal to the knives 16 and 18 as the strip leaves the tube. Since one or another of the side walls of the tube will serve to guide comparatively wide strip material the guide pins are 55 not needed and are mounted in such a way that they can be removed when wide material is being used. To this end the bridge 104 is pivotally carried by a finger 106 which is mounted upon a stud 108 for pivotal movement in a vertical plane, the stud 108 in turn being mounted upon a pin 110 for pivotal movement in a horizontal plane. The finger 106 has a handle 112 by which the pins can be moved out of the openings in the tube, the finger being movable first heightwise and 60 then laterally. A spring 114 is arranged to force the handle 112 upwardly to hold the pins in position when they are located in their openings.

65 The strip severing mechanism is located immediately in advance of the forward end of the tube 38 and comprises a fixed knife 16, Fig. 1, and a movable knife 18 between which the strapping is advanced during the movement of the feed roll. The knife 18 is mounted for movement heightwise of a bracket 116 and is carried 70 at the lower end of a plunger 118 normally forced

in an upward direction by a spring 120 positioned between the bracket 116 and an abutment 121 at the upper end of the plunger 118. The knife 18 is operated by a treadle 122 through a treadle rod 124 connected to a slide 125 which, at its upper end, carries a finger 126 upon which is pivotally mounted a latch 128 having a hooked end 130 which is normally forced into engagement with the upper surface of the spring abutment 121 by a spring 132. The latch 128 is provided with a depending arm 134 having a cam surface 136 arranged upon downward movement of the latch to engage a pin 138, on an adjustable arm 139, thus to move the latch in a clockwise direction to release it from the spring abutment 16 and 18 have severed a piece of strapping. 15

When the treadle 122 is released a spring, not shown, raises it causing the latch to move upwardly relatively to the abutment and the spring 20 132 moves the latch to reengage the upper surface thereof.

The spray device 20 is of a type well known to the art and is provided with means for spraying adhesive such as rubber latex which is supplied 25 to the sprayer through a tube 140 from a container 142 carried on the top of the machine, the latex being drawn by suction through the spray nozzle by compressed air supplied through a tube 144, the spray operation being controlled by a 30 valve 146 operated by a handle 148 pivoted upon the operating device at 150. The nozzle of the spray device is inclined at an angle to the horizontal, as shown in Figs. 1 and 5, and is arranged to direct a jet of adhesive toward a limited marginal portion of an insole presented to the tack nozzle 12. The spray is operated in timed relation to the feeding and wiping operation by means connected to the tack separator device 30. This device is carried by an arm 152 (Figs. 1 and 40 4) carried by a bracket 154 mounted for angular movement about the axis of a pivot rod 156 which carries, at its upper end, a fork 158. The rod 156 is actuated by a bell-crank lever having an arm 160 operatively connected to the fork 158, 45 and an arm 162 which engages a cam 164 on the main shaft 32. The arrangement is such that the tack separator device is moved into position to engage tacks in the raceway to maintain them in position prior to a tack inserting operation. The valve of the spray device 20 is conveniently operated at the same time by a link 166 connected to the bracket 154 and carrying a spring-pressed plunger 168 adapted to engage the free end of the link 148 to cause the latter to 50 depress the valve 146. During this time the insole upon its last is held in position with the edge portion thereof adjusted to the nozzle 12 with the fingers of the operator holding a strip of material to be attached to the insole with the end 55 thereof slightly projecting above the edge of the insole and located laterally in alignment with the spray nozzle. This results in latex being applied to the insole immediately in advance of the end of the strip. The heightwise position of the shoe is controlled by an abutment 170 secured to a portion of the frame by a bolt 172 (Fig. 4), and which is arranged to engage the face of the insole. 60

65 After the adhesive has been applied to a portion of the insole the wiper 26 is moved laterally thereover to press the end of the strapping down upon the sprayed area. As shown, the wiper is mounted upon a slide 174 mounted in a recessed portion 176 in the frame. The slide is arranged 70 75

to be reciprocated intermittently immediately subsequent to the spraying operation by links 178 and 180 which are actuated by a spindle 182 secured to an end of the link 180 and to the bell-crank lever 160, 162, of the tack separator control mechanism. The wiper 26 is shown in its advanced position in Fig. 6. The wiper has a slot 184 in the end thereof through which a tack may be driven temporarily to secure the end of the strapping in position on the insole while the adhesive is setting.

After the wiping operation just described has been completed the tack-inserting mechanism is operated to drive a tack through the end of the strapping and insole and into the last. It is to be noted that depression of the treadle 122 to effect an operation of the knives 16 and 18, causes movement of the slide 125 which carries a member 186 effective to operate mechanism to initiate operation of a one-revolution clutch to rotate the main shaft 32. This mechanism is not shown herein but may be of any suitable type such as that illustrated in the aforementioned Letters Patent.

In the operation of the machine, the strip material or strapping S is advanced by hand past the feed roll 14 through the tube 38, past the knives 16 and 18 by a sufficient distance to provide an adequate length of strap for the first piece to be attached to the insole. The operator then holds the end of the strapping along the side of the last with a small portion of the end thereof projecting above the insole adjacent to the point where it is to be attached and the shoe is presented to the abutment 170 with the end of the strapping in line with the wiper 26 and spray nozzle 20. The operator then adjusts the knob 64 to the length of the next strap which will be required and steps on the treadle. This initiates operation of the machine by means of a clutch (not shown) and the projecting piece of strapping is cut off by the knives 16 and 18 so that an individual strap is produced. The valve 146 of the spray nozzle is operated to spray cement upon the insole adjacent to an end of the strap which is being held by the operator and the wiper 26 is caused to move outwardly to wipe the end of the strap over the cemented area of the insole after which the machine drives a tack through the end of the strap temporarily to secure it in position leaving the strap hanging.

This operation is repeated until the ends of several straps are attached to the insole on one side thereof. The feed mechanism is then set by means of the knob 64 so that no feeding will take place after a tacking operation. The free ends of the straps are then successively stretched over the last and are secured to the other side of the insole in the manner above described.

Having described my invention, what I claim as new and desire to secure by Letters Patent of the United States is:

1. A machine for operating upon shoes comprising means for pressing an end of a piece of strip material against an insole presented to the machine, means for driving a fastening through the end of the strip material to secure the latter to the insole, strip severing means, and means operable subsequently to the operation of the fastening driving means to feed a strip of material a predetermined distance past the severing means.

2. A machine for operating upon shoes comprising means for pressing an end of a piece of strip material against an insole presented to the machine, means for driving a fastening through the end of the strip material to secure the latter to the insole, strip severing means, means operable to drive a fastening through an end of the strip to secure the latter to the insole, strip severing means, means operable between successive operations of the fastening inserting means to feed a strip of material past the severing means, and manually operable means for causing operation of the strip severing means prior to an operation of the pressing means.

3. A machine for operating upon shoes comprising means for pressing an end of a piece of strip material against an insole presented to the machine, means for driving a fastening through an end of the strip to secure the latter to the insole, strip severing means, means operable between successive operations of the fastening inserting means to feed a strip of material past the severing means, and manually operable means for causing operation of the strip severing means prior to an operation of the pressing means.

4. A machine for operating upon shoes comprising a spray device for spraying adhesive to a limited portion of an insole presented to the machine, means for wiping an end of a piece of strip material along the portion of the insole to which the adhesive is applied, strip severing means spaced laterally of the spray device, means operable to feed a strip of material a predetermined distance past the strip severing means, and means for causing operation of the strip severing means prior to an operation of the spray device.

5. A machine for operating upon shoes comprising means for spraying adhesive upon a portion of an insole presented to the machine, a wiper operable to press an end of a strip of material along a portion of the insole to which adhesive is applied, means for driving a fastening through the end of the strip temporarily to secure the strip to the insole, strip severing means, and means for feeding strip material past the severing means subsequent to the fastening inserting operation.

6. A machine for operating upon shoes comprising fastening inserting mechanism, a reel for strip material, strip severing mechanism, intermittently operated means for feeding strip material past the severing mechanism, means for spraying adhesive along a limited area of an insole presented to the fastening inserting mechanism, means for wiping an end of the strip along the portion of the insole to which adhesive has been applied, and means operable subsequent to the operation of the wiping means for causing the fastening inserting mechanism to drive a temporary fastening through the end of the strip to secure the strip to the insole.

7. A machine for operating upon shoes comprising fastening inserting mechanism, strip severing mechanism spaced transversely of the fastening inserting mechanism, a reel for strip material, means for feeding strip material from the reel past the strip severing mechanism and including a feed roll, means for driving the feed roll comprising a shaft, a friction disk mounted upon the shaft, a rotary drive shaft, a second friction disk arranged to engage the first-mentioned disk and slidably mounted upon the drive shaft for movement radially of the first-mentioned disk, and manually operated means for varying the position of the second-mentioned disk relatively to the first-mentioned disk thereby to vary the extent of feed movement imparted to the strip.

8. A machine for operating upon shoes comprising fastening inserting means, means for feeding strip material toward the fastening inserting means, and means for severing a piece from the strip, said means comprising a spring-pressed plunger, a knife carried by the plunger,

- an arm mounted for movement heightwise of the machine, a latch carried by the arm and normally arranged to engage a portion of the plunger, a treadle for initiating operation of the machine 5 and operatively connected to the arm for operating the latch to cause an operation of the knife, a cam on the latch, and a stud for engaging the cam arranged to release the latch subsequent to a severing operation.
10. In a machine for operating upon shoes, a reel for strip material, strip severing means, means for advancing strip material toward the severing means in combination with a guide for the strip material comprising a pivotally mounted 15 arm, and a plate carried by the arm and having in its periphery notches of different widths for guiding strip material of various widths, a flat

member over which the strip material passes, and resilient means for forcing the plate toward the member.

10. A machine for operating upon shoes comprising a reel for strip material, a strip severing knife, means for advancing strip material from the reel toward the severing knife, a flat member along which the strip material passes during its feed movement, a guide for the strip material comprising a member having a plurality of depending portions adapted to embrace the material to limit lateral movement thereof, means for mounting the guide comprising a link to which the guide is pivotally secured, and means for mounting the link for angular movement into 15 position in which the guide is inoperative.

JACOB S. KAMBORIAN.
